UNITED STATES PATENT OFFICE.

JOHN J. GARD, OF HARVEY, ILLINOIS, ASSIGNOR TO BUDA COMPANY, OF CHICAGO, ILLINOIS, A CORPORATION OF ILLINOIS.

CROSSING-GATE.

1,196,853.

Specification of Letters Patent. Patented Sept. 5, 1916.

Application filed June 1, 1915. Serial No. 31,384.

To all whom it may concern:

Be it known that I, JOHN J. GARD, a citizen of the United States, and a resident of Harvey, in the county of Cook and State of Illinois, have invented new and useful Improvements in Crossing-Gates, of which the following is a full, clear, and exact description of the invention, reference being had to the accompanying drawings, forming a part hereof.

My present invention relates to crossing gates, and has reference more particularly to that type of crossing gate wherein motor driven actuating mechanism is employed to raise and lower the gate. In this type of gate, heretofore, the provision of a braking device was found necessary for checking further movement of the motor after the breaking of the energizing circuit, such further movement being in excess of that required to bring the gate into either of its limiting positions. The principal object of this invention is to produce an improved form of actuating mechanism for crossing gates, which is constructed to obviate the necessity for providing the customary motor brake and its appurtenances, consequently reducing the initial cost and maintenance of the gate, and eliminating the operative step of applying and releasing the brake each time the energizing circuit was broken and cut in at the extremes of gate movement.

My invention further contemplates the provision of an arrangement of parts in such mechanism designed to simplify its construction and increase its efficiency and utility to a marked degree.

These, together with such other objects as may hereinafter appear, or are incident to my invention I attain by means of a construction, illustrated in preferred form, wherein:—

Figure 1 is a longitudinal section taken through the gate post illustrating the application of my improved mechanism thereto, the gate being shown in lowered position;

Figure 2 represents a side elevation of the same taken at the left hand of Figure 1, and—

Figure 3 is a front view of a portion of the structure as shown in Figure 1, illustrating the relation of the parts when the gate is in its raised position.

Figure 4 is a sectional view taken along 55 the line 4—4 of Figure 3.

Referring to the drawings, it will be seen that I provide the gate post 4 with the usual motor 5 and gate 6, the latter being mounted on a shaft 7 which carries a bell crank lever 8 to one end of which is coupled the short gate 9. Within the post is a standard in whose base portion 10 is journaled a shaft 11 carrying thereon a worm 12 designed to drive a worm gear segment 14 whose shaft 13 is mounted in the upwardly projecting spaced arms 10^b of the standard. Suitable drive connections are provided between the motor shaft 5^a and the worm shaft 11, and as shown, may consist of the sprockets 15, 16, chain 17 and the gears 18 and 19, the sprocket 16 and the gear 18 being carried on a counter shaft 20 which has a bearing in the base 10. The shaft 13 is provided with a contact plate 13^a; but for the sake of brevity and clearness, the wiring and contact connections are not here shown, a preferable form of the same being disclosed in my patent N° 1,049,840 of January 7, 1913, which may, if desired, be employed in connection with my present invention.

Extending from the other end of the lever 8 to the worm gear segment is a connecting rod 21 terminating at its lower end in a fork 21^a which is operatively attached to the web 85 of the segment 14. It will be understood, of course, that rotation given by the motor to the worm in one direction imparts movement substantially on a half-turn to the segment in order to raise the gate, and reverse 90 rotation of the worm serves to lower it, the driving relation continuing just so long as the teeth of the worm and worm gear segment are in operative engagement, and ceasing when disengaged or out of mesh. Any 95 excess rotative movement of the motor occurring subsequent to the breaking of the energizing circuit and during this disengagement obviously can have no effect on the segment itself.

Means are also provided to limit the movement of the segment and to insure prompt operative engagement or meshing of the teeth of segment and worm upon reverse rotation of the latter. With this end in view, 100 I provide the segment with a stop bar 22, and formed on the standard base 10 at each side of the worms are stop lugs or abutments

26 and 27 which are disposed to coöperate with the bar 22, and at a time or times coincident, or substantially so, with the unmeshing or disengagement of the teeth. As already indicated, and as shown in Figures 1 and 3, respectively, this disengagement occurs at the completion of worm gear movement in one direction to close the gate and in the reverse direction to open the gate.

10 A reference to the drawings will show that the bar 22 is so located with reference to the abutments and the point of teeth disengagement as to be capable of a slight yielding movement when contacting with the former, which movement occurs just prior to the disengagement of the teeth. In this connection, I preferably employ the interposed spacing member 24 which is mounted on the rear face 14^a of the segment, and upon whose arms 23, 23', is carried the bar 22 by means of the headed bolts 24^a which pass through the bar and arms and extend past the latter to receive thereon the coil springs 25 which serve to permit the yielding movement above referred to.

From the foregoing, it will be obvious that when the driving relation of the worm and gear is complete any excess rotary movement of the motor and worm in the same general direction is not communicated to the gear and cannot possibly have any effect on the gate actuating mechanism, of which the said gear forms a part, but at the same time the beveled outer flanks of the end 30 teeth of worm and worm gear, 28 and 29 respectively, are yieldingly held in an abutting relation in readiness for reverse rotative movement of the motor. On such movement being communicated to the worm, a 35 prompt meshing or operative driving engagement of worm and gear teeth is obtained, whereupon the other limiting position of the gate is quickly reached, bringing the flanks of the other outer teeth in a similarly yieldingly-held relation, as will be readily understood.

The arms 10^b are spaced apart to provide clearances at each side of the segment gear for the free movement therein of the connecting rod fork 21^a from the position shown in Figure 1 to that in Figure 3, and vice versa. As clearly indicated in the drawings, the stop lugs are positioned intermediate the arms 10^b and out of the path of the segment teeth, the stop bar 22 projecting sufficiently therebeyond to co-act with the lugs. Furthermore, the post 4 may be provided with the end opening 4^a of a sufficient dimension as to permit the entrance therethrough 50 of the motor and mechanism *en bloc*, the rod connection being made through the top end opening 4^b covered by the cap 30, the plate 31 serving as a closure for the side opening 4^a.

55 I do not intend to limit myself to the con-

struction precisely as shown, nor to the exact arrangement of the parts, for it will be obvious that variations therefrom may be made without in any way departing from the spirit and scope of my invention as 70 pointed out in the appended claims. Any reference in the claims to the engaging and disengaging of the teeth relates to an operative driving engagement and a releasing from such relation.

Having thus described my invention, and illustrated its use, what I claim as new and desire to secure by Letters Patent, is the following:

1. In a device of the character described, the combination of a post, a shaft journaled therein, a gate mounted on said shaft to rotate with it, a motor operated driving gear, a driven gear member, a crank connection between the driven member and said shaft, said driven member being constructed for engagement with said gear to actuate the arm to its vertical and horizontal operative positions and for disengagement therefrom, as an operative position is reached, and stop means for the driven member disposed out of the path of said crank connection and coöperating to retain the members when disengaged in an abutting relation whereby to insure a driving engagement therebetween upon reverse rotation of the driving gear member.

2. In a device of the character described, the combination of a gate post, a gate thereon adapted to assume alternate raised and lowered operative positions, actuating means comprising driving and driven gears constructed and arranged for disengagement as the gate reaches an operative position, and a stationary stop means, said driven gear operatively connected at one portion thereof with said gate and provided at another portion thereof with a stop member movable with said driven gear and adapted to engage with said stop means as the gears disengage.

3. In a crossing gate, the combination of a gate, a frame, and motor operated actuating means for said gate mounted in said frame comprising associated but normally disengaged driving and driven gears, a stop member formed within said frame adjacent said driving gear, and a spring held stop member mounted on the driven gear and movable therewith to co-act with the other stop member and yieldingly maintain the normal relation of the gears.

4. In a railway crossing gate, the combination of a frame having a base portion and upwardly extending spaced arms, gate actuating means comprising a driving gear and a driven gear journaled in said base and arms respectively, an abutment formed on said base and disposed out of the path of said driven gear, and a stop member

ried by said driven gear to co-act with said abutment, substantially as and for the purpose set forth.

5. In a crossing gate, and in combination, a frame, a gate thereon, motor operated actuating means for said gate comprising associated but normally disengaged driving and driven gears, spaced stop members disposed with reference to the driving gear, 10 and a yieldable stop member movable with the driven gear and projecting therefrom to yieldingly engage with either of the first mentioned stop members as the gears disengage, all of said members being disposed 15 out of the path of the gears during the actuation of the gate.

6. In a device of the character described, the combination of a post, a shaft journaled therein, a gate thereon, motor operated actuating means therefor comprising gearing provided with a movable connecting rod extending substantially vertically therefrom to the shaft and capable of reciprocation by 20 said gearing to raise and lower the gate, spaced stop members in said post, members of said gearing being constructed and arranged for disengagement as the gate reaches a limiting position, and one of said 25 gearing members formed with a portion extending therefrom to co-act with one of the said stop members for insuring the reengagement of said gearing members to actuate the gate to its other limiting position, substantially as described.

30 7. In a device of the character described, the combination of a post, a shaft journaled therein, a gate associated with said shaft

and movable to assume alternate raised and lowered operative positions, actuating means therefor connected with said shaft and comprising driving and driven gears adapted to disengage as the gate reaches an operative position, and stop means in said post comprising members co-operative as the gears disengage, one of said members carried by 40 the driven gear and movable therewith to engage another of said members whereby to insure a driving engagement between the gears upon reverse rotation of the driving gear.

50 8. In a device of the character described, the combination of a post, a gate pivotally mounted thereon and adapted to assume alternate raised and lowered operative positions with reference to said post, motor operative actuating means therefor comprising associated driving and driven gears constructed and arranged for disengagement as the gate reaches an operative position, said driven gear provided with operative connections to said gate and having a stop member movable therewith independently of said connections, and fixed stop means located out of the path of said operative connections and engageable by said stop member as the gears disengage.

55 In testimony whereof I have hereunto signed my name and affixed my signature in the presence of the two subscribed witnesses.
